BY O'Brien & Co.

his ATTORNEY^S.

UNITED STATES PATENT OFFICE.

LEWIS E. LEMEN, OF DENVER, COLORADO.

NUT-LOCK.

SPECIFICATION forming part of Letters Patent No. 350,143, dated October 5, 1886.

Application filed June 24, 1886. Serial No. 206,142. (No model.)

To all whom it may concern:

Be it known that I, LEWIS E. LEMEN, a citizen of the United States, residing at Denver, in the county of Arapahoe and State of Colorado, have invented a new and useful Improvement 5 in Nut-Locks, of which the following is a specification, reference being had therein to the accompanying drawings, in which similar letters refer to corresponding parts.

10 My invention relates to improvements in nut-locks; and the object of my improvement is to provide a nut lock especially adapted for locking the nuts used to secure the fish-plate forming railroad-rail joints, but may be used 15 as well for locking nuts in other positions, as hereinafter fully described and set forth.

In the drawings, Figure 1 is a top view of my improved nut-lock. Fig. 2 is a side elevation of my improved device, showing one 20 of the wrenches upraised. Fig. 3 shows my nut-lock attached to a rail-joint and in position for use. Fig. 4 is an end view of a rail-joint with my improved device attached. Fig. 5 shows a spring-key used in connection with 25 my improved device. Fig. 6 is a cross section of the same.

My invention consists of the plate *a*, provided with the openings *a'* and *a''*, as shown in Fig. 1. This figure shows a lock prepared 30 for securing four nuts, but may be constructed for more or less nuts, as may be desired. At each end of plate *a* is hinged a wrench, *b*, secured in socket *b'* by a suitable rivet, but allowed to move freely on said rivet, as shown 35 in Fig. 2. When in position for use, as shown in Figs. 1 and 3, the wrenches *b* are held fast in said position and in contact with plate *a* by means of the socket *c* and the spring-keys *d*. The construction of keys *d* is shown in Figs. 40 5 and 6. Sockets *c* are fashioned to receive arms *b''* of wrenches *b*, and also keys *d*, which pass through said sockets and said arms, and securely hold said wrenches in place when the

lock is in use. Each socket *c* consists of two lugs integral with plate *a*.

In the use of my improved device the same is placed over the fish-plate on the side of the joint where the nuts are placed which secure the necessary bolts. The two nuts nearer the center of the plate should be in position on the bolts when my lock is placed upon the fish-plate. These nuts are secured within the square or rectangular opening *a''*, and securely locked by means of the flanges *e*, formed on two opposite sides of said opening. We will now suppose the keys *d* to be removed from the socket *c*, and that the wrenches are raised up from plate *a* to any desired position, as aforesaid. The two outer nuts which secure the bolts received within the openings *a'* are then placed in position, being in contact with plate *a*, so as to hold it securely against the fish-plate. The wrenches *b* are then dropped over these nuts, the spring-keys *d* placed within socket *c*, and my improved nut-lock is in position for use.

Having thus described my invention, what I claim, and desire to secure by Letters Patent, is—

In a nut lock, a plate provided with one or more square or rectangular openings with flanges on two opposite sides, said openings being suitable for the reception of nuts, and provided with one or more openings, *a'*, for the reception of bolts, said plates being also provided with one or more hinged or movable wrenches, *b*, which may be dropped down over the nut or nuts after the nuts are placed in position, said wrenches being held in position, when in use, by means of suitable sockets, in which are placed spring-keys, substantially as described.

LEWIS E. LEMEN.

In presence of—
J. B. WILLSEA,
W. SMEDLEY.
